UNITED STATES PATENT OFFICE.

JAMES C. COVERT, OF WATERVLIET, NEW YORK, ASSIGNOR TO THE COVERT MANUFACTURING COMPANY, OF SAME PLACE.

DESIGN FOR A HOOK.

SPECIFICATION forming part of Design No. 33,409, dated October 23, 1900.

Application filed September 20, 1900. Serial No. 30,827. Term of patent 14 years.

To all whom it may concern.

Be it known that I, JAMES C. COVERT, a citizen of the United States, residing at Watervliet, in the county of Albany and State of New York, have invented and produced a new and original Design for Hooks; and I do hereby declare the following to be a full, clear, and exact description of the same, reference being had to the accompanying drawings, 10 forming a part thereof.

This invention relates to a new and original design in hooks; and it is embodied in the structure having the form and configuration shown in the accompanying drawings.

- 15 In the drawings, Figure 1 is an elevation of the hook embodying the essential features of the design, and Fig. 2 is an edge view looking down on the construction shown in Fig. 1.
- 20 The design, as shown, consists generally in a body portion A, fashioned with a substantially-straight lower edge and having the upwardly and inwardly extending hook portions B and B', the points of which are tapered in 25 one direction. Midway between the hooked ends is an extended portion C, having an up-

per edge substantially straight and its opposite ends formed with curved seats or recesses D, extending down to the upper edge of the body portion A. The said upper edge of the 30 body portion A has slight protuberances or projections a thereon.

The design, as above described and shown, relates more generally to the general contour and formation of the hook, the essential feature being the positioning of the hook portion of the body with the extensions arranged on the body in a plane midway between the ends of the hooks and fashioned substantially as shown. 35

Having thus described the invention, what is claimed as new, and desired to be secured by Letters Patent, is—

The design for a hook, substantially as shown and described.

In testimony whereof I affix my signature in presence of two witnesses.

JAMES C. COVERT.
